UNITED STATES PATENT OFFICE.

DUNCAN J. FISHER, OF KEYSTONE, MONTANA.

FALSE SET.

1,199,168.

Specification of Letters Patent. Patented Sept. 26, 1916.

Application filed September 13, 1913. Serial No. 789,627.

To all whom it may concern:

Be it known that I, DUNCAN J. FISHER, a citizen of the United States, residing at Keystone, in the county of Missoula and State of Montana, have invented new and useful Improvements in False Sets, of which the following is a specification.

This invention relates to an improved false set.

10 The object of the invention is to provide a false set for use between the permanent set and the breast in working drifts or tunnels, wherein it is desired to prevent loose earth or rock or gravel from falling in.

15 A further object is to provide a false set, which may be substituted for one of the broken permanent sets to hold or support the top spiling or lagging in place until a new permanent set has been positioned.

20 A further object is to provide a false set, which will not only support the breast but which will also support that portion of the top and side spiling extending from the breast to the permanent sets.

25 A still further object is to provide a false set in which means are provided for successively building up or positioning the breast boards and supporting the same while the bore of the tunnel is being worked.

30 Still further objects and novel features of construction will be more fully described in connection with the accompanying drawings, and will be more particularly pointed out in and by the appended claim.

35 In the drawings:—Figure 1 illustrates one form of my improved false set, showing the same interposed between a permanent set and the breast of a drift or tunnel which is being worked. Fig. 2 is a perspective view of detached portions of one of the false upright posts, showing the parts in approximate relative positions such as they would assume when assembled. Fig. 3 is a view in elevation of a breast rod with 45 coacting portions therefor in section.

Like characters of reference designate similar parts throughout the different figures of the drawings.

For purposes of illustration, I have shown 50 my improved false set positioned for working a drift or tunnel and between the breast 1 and the permanent set which latter may comprise upright timbers 2 and a horizontal top beam 3. Side spiling is indicated at 4 and top spiling at 5, and I have shown enough of the same to illustrate how this

spiling is prevented from falling inwardly or downwardly at points between the permanent set and the breast.

Referring more particularly to the structure constituting my invention, the numeral 6 designates, generally, two upright false set post structures, which may be mounted or supported on jack boxes 7. The jack boxes 7 rest upon a spacing plate 8 which may be provided with one or more ribs 9 to hold the jack boxes against inward displacement and to more firmly foundation the false posts 6. On the upper ends of the false posts 6, I dispose a false sill or beam 10, which not only serves to support the top spiling 5, but which is also constructed to resist inward displacement of the upper ends or tops of the posts 6, as will herein-after more fully appear. The false set 73 posts 6 are supported against movement rearwardly from the breast 1 by strut rods 11 and 12 adapted to be interposed between the false set posts and the permanent set. The breast boards 13 are supported by the 30 false set posts 6 by a plurality of breast rods 14.

Referring more particularly to the specific construction of the posts 6, 15 and 16 designating side upright slabs, preferably formed 35 of metal, and which constitute the sides of the skeleton posts 6. The side 16 is provided with holes 17 near that margin thereof which is disposed nearest the breast 1. Said side 16 is also provided with holes 90 18 disposed rearwardly or inside of the holes 17. The opposite margin of the side 16 is provided with supporting notches 19, the purpose of which will presently appear. The side 15 is provided with supporting 95 notches 20 and also with supporting notches 21. Near the opposite margin, said side is provided with holes 22. The slabs or sides of each post are provided with a base, which may be in the form of a base plate 23, and the side margins thereof are recessed in dove tailed form, as indicated at 24. The lower ends of the slabs are provided with dove tails 25 and 26, shaped to fit the dove tailed recesses 24, thereby structurally uniting the side slabs with the base plate against any lateral movement outwardly of the former. The side slabs are shouldered at 27 and 28 for engagement with the base plate, so as to structurally support the slabs 100 on said plate against downward movement with respect thereto. I may connect the side

105

110

slabs with their base plates by screws 29, if desired. The base plate 23 is provided with an opening 30 to receive the upper end of a jack screw, the enlarged turning hub of which is indicated at 31 and is provided with openings to receive a jack rod or like implement, not shown. The lower end 32 of the jack screw has threaded engagement in the upper wall of jack box 7, and it will 10 be readily seen from the foregoing that the false set post 6 may be jacked up or down to the proper elevation.

The upper ends of the slabs 15 and 16 are connected by a cap 33, which is preferably of channel shape in cross section. The web 34 of the cap is mortised at 35 to receive tenons 36 and 37 formed on the slabs 15 and 16. The mortises 35 suitably shoulder the cap 33, so that at its end portions it 20 rests upon the top edges of the slabs 15 and 16. The slabs may be united to the cap by screws 38.

Mid-braces 39, preferably in the form of plates, are provided with studs 40 adapted 25 to fit holes 41 and 42 in slabs 15 and 16. Key projections 43 are adapted to fit notches 44 and 45 so that the mid-braces will be structurally locked to the slabs 15 and 16 when the posts are assembled.

30 The channel caps form seats for the ends of a false set beam or sill 10, and the latter at one end is reduced to form an outwardly facing shoulder 46 for engagement with the web of the cap to resist inward movement 35 of the post. The beam 10 is provided with a head 47, which is telescopically adjustable in the beam 10, the head 47 having a reduced shank 48 slidably projecting into the beam 10. Set screws 49 are provided to lock 40 the extensible head so as to adapt the beam for tunnel work of different widths. The head 47 is recessed so as to provide an outwardly spacing shoulder 50, adapted to engage the web of the cap and the outer portion 45 of the head seats in the channel of the cap.

The manner in which the posts 6 are set up and braced will clearly illustrate how they are adapted to support the side spiling 50 4 against inward buckling while it will be clear that the top spiling is supported by the beam 10.

One of the breast rods is illustrated in detail in Fig. 3, and the same may consist of 55 a shank or rod portion 51 having a ball 52 adapted to be socketed in a two-part base 53. The parts of the base may be held together in any desirable manner, and the base 53 is adapted to rest against the breast 60 boards 13. The rod portion 51 may be provided with a hexagonal enlargement 54 and also with radial bores 55, whereby the rod may either be adjusted by a wrench or a turning bar. The opposite end of the rod 65 14 is threaded, as indicated at 56, for en-

gagement with a rod head 57. The rod head may be in the form of a spindle having trunnion ends 58 adapted to seat in the notches and holes of the posts 6, in a manner which will now be described. It may be stated 70 that the strut rods 11 and 12 are similar in construction to the breast rods 14, therefore a detailed description of Fig. 3 will suffice.

I will now describe the manner in which the false posts 6 are supported by the strut 75 rods.

The bases of the strut rods 11 and 12 are disposed against the uprights 2 of the permanent set, and the trunnions of the heads are disposed in holes 22 and notches 19 of 80 the post slabs. The strut rods are then turned or jacked in their heads to impart the desired supporting stress to the posts 6 against movement toward the permanent set. As the tunnel is worked, one or more breast 85 boards 13 may be positioned in place and held against the breast by the breast rods 14. The bases of the breast rods 14 engage the breast boards, and the heads of the breast rods have their trunnions journaled in the 90 notches 20 and holes 17 of the slabs 15 and 16, respectively. The breast rods will be jacked in their heads to obtain the desired stress of engagement against the breast boards. After all of the breast boards 13 95 have been positioned in place, the breast planks 59 will be positioned, as shown. Plank rods 60, similar in all respects to the strut and breast rods, but the heads of the plank rods, or rather the trunnions on one 100 side of the heads thereof, are journaled in holes 18, while their opposite trunnions are seated in notches 21. The disposition of the holes 18 with respect to the holes 17 provides for slightly canting the plank rods 60 105 with respect to the breast rods 14. After the breast planks are in place, it will be seen that the breast rods can be removed, as the plank rods will hold all of the breast boards 110 in place. However, it will be necessary to tighten up the successively positioned breast boards, completely, before the breast planks can be located in position.

While I have herein shown and described 115 false set posts of sectional skeleton formation, it will be understood that they may be made in one piece if the advantageous feature of adjustment by the jacks, together with other features, can be dispensed with and the posts made of different sizes to accommodate different classes of work.

The ease and facility with which this false set can be positioned will be readily understood from the foregoing, and the advantage of a clear and unobstructed interior for 125 freedom of the workmen in the false set will likewise now be clearly apparent.

While I have herein shown and described one specific utility and embodiment of my invention, I do not wish to be limited there- 130

to except for such limitations as the claim
may import.

I claim:—

In a false set for excavation work, up-
rights, strut rods, heads for said rods hav-
ing threaded engagement therewith and pro-
vided with trunnions adapted to be journaled
in said uprights, the opposite ends of said
strut rods having balls formed thereon, and

socket bases for the balled ends of said rods, 10
substantially as described.

In testimony whereof I hereby affix my
signature in the presence of two subscribing
witnesses.

DUNCAN J. FISHER.
